No. 638,598.

V. J. ROBERTSON.
CHURN.

Patented Dec. 5, 1899.

(Application filed Sept. 6, 1899.)

(No Model.)

UNITED STATES PATENT OFFICE.

VIOLA J. ROBERTSON, OF WEATHERFORD, OKLAHOMA TERRITORY.

CHURN.

SPECIFICATION forming part of Letters Patent No. 638,598, dated December 5, 1899.

Application filed September 6, 1899. Serial No. 729,593. (No model.)

To all whom it may concern:

Be it known that I, VIOLA J. ROBERTSON, a citizen of the United States, residing at Weatherford, in the county of Custer and Territory of Oklahoma, have invented certain new and useful Improvements in Churns; and I do declare the following to be a full, clear, and exact description of the invention, such as will enable others skilled in the art to 10 which it appertains to make and use the same.

The invention relates to improvements in churns, and more particularly to that class known in the art as "reciprocating body-workers;" and the object is to simplify and improve the construction and increase the efficiency of the churn with a minimum expenditure of power.

To this end the invention consists in certain features of construction and combination of parts, which will be hereinafter fully described and claimed.

In the accompanying drawings, Figure 1 is a perspective view of my improved churn. Fig. 2 is a longitudinal section of the same. 25 Fig. 3 is a transverse central section.

In the drawings the same reference characters indicate the same parts of the invention.

11 denote the parallel base-plates, which 30 support the longitudinal arch 2, and 33 denote the transverse parallel stirrups, mounted in the arch and having their lower ends terminating in the lateral toes 44, which are pivoted in the longitudinal side rails 55, the 35 ends of which carry the vertical uprights 66, which support the longitudinal bench 7, and 88 denote limit-straps extending from the outer ends of the bench to the base-plates to limit the movement of the bench in either direction.

The upper face of the bench is formed with a pocket 9 to receive the churn-body, which snugly fits between the parallel shoulders 10

10, forming the transverse parallel end walls of the pocket.

The churn is provided with a removable screw-cap 12 and with guide-eyes 1313 to receive the straps 1414, fixed to the side edges of the bench and adapted to removably secure the churn-body in place.

From the manner in which the bench is swung from the arch it will be seen that the bench and churn are capable of having two independent movements—a longitudinal reciprocating movement to churn the cream and bring the butter and a lateral oscillating movement to axially rock the churn-body and collect the butter.

It will of course be understood that various changes in the form, proportion, and the minor details of construction may be resorted to without departing from the principle or sacrificing any of the advantages of this invention.

Having thus described the invention, what is claimed, and desired to be secured by Letters Patent, is—

In combination, the transverse base-plates, the longitudinal arch supported in said base-plates, the transverse stirrups centrally pivoted in said arch, the longitudinal parallel side rails pivoted in the lower ends of said stirrups, the vertical uprights fixed to said rails, the recessed bench fixed to said uprights, the limit-straps connecting the ends of the bench and base-plates, and the transverse retaining-straps fixed to the side edges of the bench and extending across the pocket, substantially as and for the purpose set forth.

In testimony whereof I have hereunto set my hand in presence of two subscribing witnesses.

VIOLA J. ROBERTSON.

Witnesses:

BECKS ENCK,
H. P. BAILEY.
